US0D1032003S

(12) **United States Design Patent** (10) **Patent No.:** **US D1,032,003 S**
(45) **Date of Patent:** **** Jun. 18, 2024**

(54) **WARMER**

(71) Applicant: **Kobayashi Pharmaceutical Co., Ltd.**,
Osaka (JP)

(72) Inventor: **Tsuyoshi Igaue**, Osaka (JP)

(73) Assignee: **Kobayashi Pharmaceutical Co., Ltd.**,
Osaka (JP)

(**) Term: **15 Years**

(21) Appl. No.: **29/805,195**

(22) Filed: **Aug. 25, 2021**

(51) LOC (14) Cl. **24-01**

(52) U.S. Cl.
USPC **D24/206**

(57) **CLAIM**

The ornamental design for a warmer, as shown and described.

DESCRIPTION

FIG. 1 is a front perspective view of a warmer showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front view thereof in an alternative configuration;

FIG. 10 is a front perspective view of a warmer showing the claimed design

FIG. 11 is a rear perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is a front view thereof in an alternative configuration.

1 Claim, 10 Drawing Sheets
